The ornamental design for a lamp with speaker, as shown and described.

DESCRIPTION

FIG. 1 is a perspective view of a lamp with speaker showing our new design;

FIG. 2 is a front view thereof;

FIG. 3 is a rear view thereof;

FIG. 4 is a left side view thereof where the right side view is a mirror image;

FIG. 5 is a top plan view thereof;

FIG. 6 is a bottom plan view thereof; and,

FIG. 7 is a reference view showing the state that a mobile phone is attached to the subject design.

The stipple shading and the straight line shading illustrate a contrasting appearance.

The broken lines in FIG. 7 show environmental structure only and form no part of the claimed design.
